US00D811329S

(12) **United States Design Patent** (10) Patent No.: **US D811,329 S**
(45) Date of Patent: ** Feb. 27, 2018

(54) **POWER ADAPTER**

(71) Applicant: **Google Inc.**, Mountain View, CA (US)

(72) Inventors: **Rachael Elizabeth Roberts**, San Francisco, CA (US); **Bernardo Núñez Rojas**, San Francisco, CA (US); **Phan Thao Benno Dang**, San Francisco, CA (US)

(73) Assignee: **Google LLC**, Mountain View, CA (US)

(**) Term: **15 Years**

(21) Appl. No.: **29/574,166**

(22) Filed: **Aug. 12, 2016**

Related U.S. Application Data

(62) Division of application No. 29/501,588, filed on Sep. 5, 2014, now Pat. No. Des. 772,160.

(57) **CLAIM**

The ornamental design for a power adapter, as shown and described.

DESCRIPTION

FIG. 1 is a front perspective view of a power adapter according to a first embodiment of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a front perspective view of a power adapter according to a second embodiment of our design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof;

FIG. 14 is a bottom view thereof;

FIG. 15 is a front perspective view of a power adapter according to a third embodiment of our design;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top view thereof;

FIG. 21 is a bottom view thereof;

FIG. 22 is a front perspective view of a power adapter according to a fourth embodiment of our design;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top view thereof; and,

FIG. 28 is a bottom view thereof.

The broken lines shown represent unclaimed subject matter and form no part of the claimed design. The stipple shading shown in the figures represents a contrast in appearance from the non-stippled filled areas.

1 Claim, 15 Drawing Sheets
